UNITED STATES PATENT OFFICE.

MERRICK M. BARNES, OF BOSTON, MASSACHUSETTS.

MICROMETER-CALIPERS.

SPECIFICATION forming part of Letters Patent No. 346,456, dated August 3, 1886.

Application filed August 21, 1885. Serial No. 174,956. (No model.)

To all whom it may concern:

Be it known that I, MERRICK M. BARNES, of Boston, in the county of Suffolk and State of Massachusetts, a citizen of the United States, 5 have invented certain new and useful Improvements in Micrometer-Calipers, of which the following is a specification.

My invention relates to that class of measuring-instruments known as "micrometer-calipers," and has for its object to produce improved accuracy, effectiveness, and convenience therein.

In the accompanying drawings, Figures 1 and 2 represent in side and end elevation a 15 device embodying my present invention. Fig. 3 represents in section the screw D, with its connecting parts; and Figs. 4 and 5 are sections showing, respectively, the method of clamping the screw E and of adjusting the 20 screw D, in the manner hereinafter described.

My improved micrometer-calipers consist of the usual U-shaped standard, A, the extremities of its arms carrying the caliperizing devices, as will be hereinafter more particularly described. As it is often desirable that the calipers should be used as a bench-tool, I have devised a universal joint or attachment between the calipers and the bench-plate B, which is to be screwed into the bench, as 25 shown. This attachment I will now proceed 30 to describe.

Upon the bench-plate I form a horizontal face to receive a cylindrical block, C, the lower face of which is also horizontal, and which 35 is provided with a dowel, c, entering a suitable recess in the bench-plate. The upper end of this block C is cut off at an angle of about thirty degrees to the horizon, and upon it is fitted by a similar dowel and recess a second 40 piece, C', the lower face of which is cut off at an angle matching that of the upper face of the block C. The dowel of this piece C' is shown in the drawings at c'. The standard A is made at its lower part in the form of a yoke 45 or saddle, for convenient attachment to the block C', with which it is connected in a similar manner by a dowel, a. Each of the dowels c, c', and a is provided with a suitable locking-screw, as shown, whereby it may be held 50 at any desired position.

The connection between the standard A and

the block C enables the former to be turned entirely around upon the latter, and the same is true of the connection between the blocks C' and C, and the block C and the bed-plate 55 B. By the combined use of these various adjustments, the calipers can be adjusted to a large number of different positions, as may be most convenient in use, the arrangement of blocks and dowels being substantially equivalent to the well-known ball-and-socket or so-called "universal" joint.

The two arms of the standard A carry, respectively, a pair of caliperizing-screws, D and E, the screw E serving the purpose of the anvil commonly used in instruments of this class. As shown in the drawings, this screw or anvil E may be moved backward or forward within the standard A by means of the graduated shifting-screw E'. This screw, being of large 65 diameter and quick pitch, and being graduated, as shown, enables the anvil E to be quickly and readily shifted toward or away from the opposite end of the standard which carries the caliperizing-screw D, as may be required, 70 for readily caliperizing the different sizes of work. The screw E' may be locked at any desired position by means of the lock or clamp e. This detail of construction is illustrated 75 on an enlarged scale at Fig. 4, and is a well-known device in instruments of this character.

The caliperizing-screw D, which is mounted in the opposite end of the standard A, is of ordinary construction, except that instead of 85 attaching the thumb-piece directly to the graduated shell d, which is connected with the screw D, I interpose a coiled spring between the thumb-piece D' and the shell d, attached to the arm D. This construction is illustrated 90 in section and on an enlarged scale at Fig. 3. The thumb-piece is loosely mounted upon an extension of the screw D, and a coiled spring, as stated, is interposed between the thumb-piece and the shell d, which is rigidly attached 95 to the screw D, as stated. The object of interposing this spring is as follows: In instruments of this character, intended to measure distances or thicknesses of material with great minuteness and accuracy, it has been found 100 that when the caliperizing-arm is directly or rigidly connected with the thumb-piece by

which it is turned there is liability of inaccuracy of measurement, growing out of the difference of degree of delicacy of touch in the hands of the various workmen using the 5 calipers. It frequently happens from this that different workmen, when caliperizing a piece of metal of the same thickness by means of the same calipers, will obtain different readings of the instrument. This, as has been 10 said, is due to the difference in their delicacy of touch; and it is consequently important to remove this factor of uncertainty in the operation of the machine. When a spring or similar yielding connection is inserted, it is obvious 15 that after the caliperizing-screw D has been brought up against the work any excess of force will cause the spring to be compressed and the thumb-piece D' to be turned without further turning the screw D or the shell d. 20 As this shell is graduated in the customary way with reference to a scale upon the arm of the standard A, which graduation gives a micrometer measurement of the advance or withdrawal of the caliperizing-screw D, it is manifestly desirable to have a spring or cushion 25 interposed between the collar d and the thumb-piece D', so that the screw D shall always be brought up to the work with the same force—viz., the tension of the spring. 30 As the face of the caliperizing-screw D is apt to become worn, and its measuring length thereby slightly shortened, it is desirable to provide an adjustment for this, which may be done by forming the nut d², in which the caliperizing-screw D turns, separate from the standard A and screw-threaded therein. This nut 35 may be cut away on either side at the top, as shown on an enlarged scale and in section in Fig. 5, so as to leave a rib, against which adjusting-screws d³ bear. By turning these the nut d² can be turned in either direction, and thus slightly advance or withdraw the caliperizing-screw D and the graduated shell d together to compensate for wear, and also to insure 40 an accurate adjustment of the machine when first put together. 45

My improved calipers are frequently used in caliperizing a large number of pieces of metal—as, for example, duplicate parts of machinery 50 varying only slightly in thickness. It is desirable under these circumstances, after setting the screws D and E at the distance apart which represents the standard thickness of the parts to be caliperized, to give to one of them the capacity 55 of slightly yielding, to admit of the easy introduction of the part to be caliperized. For this purpose I provide an attachment whereby one end of the coiled spring interposed between the thumb-piece D' and the 60 screw D, by which the latter is moved, may be held fixed. As this spring is attached to the screw D, it is obvious that the latter may still be turned backward slightly against the tension of the coiled spring, which at one end is 65 held fast.

I have found that a convenient way of securing one end of the coiled spring is to form

the thumb-piece D' with a series of notches in its edge, (see Fig. 2,) and to provide a sliding catch-pin, F, (best shown at Fig. 1,) working 70 in and out of a suitable slot in the arm of the standard A. It is obvious that when this catch-pin F enters one of the notches in the thumb-piece D' the latter is held fast, and as one end of the coiled spring is attached thereto, 75 it in turn is held fast. Now, if a supplemental thumb-piece, D², be for convenience placed upon the shell d, which, as has been said, is connected with the screw D, and also with the loose end of the coiled spring, it is obvious 80 that if the screws D and E be set at the right distance the shell d may be turned back two or three turns by means of the supplemental thumb-piece D², thereby increasing the distance between the screws D and E, so as to 85 allow the easy introduction of the piece to be caliperized. At the same time the coiled spring will be made tense, and as soon as the piece to be caliperized is in place, if the operator simply releases his hold of the thumb-piece D², 90 the tension of the spring will automatically bring up the screw D against the work to be measured, while at the same time its dimensions can be read by the graduation upon the shell d. In this way I obtain the advantages, 95 first, of rapid work, and, second, of the automatic tension upon the screw D, with its benefits, as previously described.

As the work to be measured is often quite as likely to run below the standard as above 100 it, it is desirable, after setting the shell d at the point representing standard thickness, to turn the thumb-piece D' one or two notches farther in the direction of the inward movement of the screw D before securing it by means of 105 the catch-pin F. When so adjusted, the calipers will show whether the work measured is standard or whether it exceeds or falls below it, and how much.

I claim—

1. In micrometer-calipers, the combination of the caliperizing-screw, its thumb-piece, and an interposed spring attached to the caliperizing-screw and also to the thumb-piece, by means of which spring and thumb-piece the 115 screw is moved up against the work under a constant tension—viz., the tension of the spring—all substantially as set forth.

2. In micrometer-calipers, the combination, with the caliperizing-screw and its thumb-piece, 120 of a spring-connection between the thumb-piece and screw, and a device, substantially as herein described, whereby one end of the spring may be held fast or prevented from moving, all substantially as set forth.

3. In micrometer-calipers, the combination of the caliperizing-screw D and the notched thumb-piece D', connected by an interposed spring, as described, and of the catch-pin F, arranged to slide in the arm of the calipers and to engage with the notches in the thumb-piece D', all substantially as set forth.

4. In micrometer-calipers, the combination of the caliperizing-screw D with its measuring-

shell d , carrying a supplemental thumb-piece, D^2 , of the thumb-piece D' , an interposed spring, as described, and a sliding catch-pin, F , for securing or holding fast the end of the spring, 5 all substantially as set forth.

5. In micrometer-calipers, the combination, with the caliper-screw D and the standard A , of a sleeve, d^2 , screw-threaded in one extremity of said standard, and opposed adjusting-screws bearing against the said sleeve,

whereby it may be turned in either direction within the standard to regulate the position of the caliper-screw.

In testimony whereof I have hereunto subscribed my name this 14th day of August, A. 15 D. 1885.

MERRICK M. BARNES.
